UNITED STATES PATENT OFFICE.

WILLIAM N. BUTTON, OF PROVIDENCE, RHODE ISLAND, ASSIGNOR TO THE JOSEPH BANIGAN RUBBER COMPANY, OF SAME PLACE.

SNOW-EXCLUDING ARCTIC.

SPECIFICATION forming part of Letters Patent No. 642,810, dated February 6, 1900.

Application filed March 30, 1899. Serial No. 711,070. (No model.)

To all whom it may concern:

Be it known that I, WILLIAM N. BUTTON, of Providence, in the county of Providence and State of Rhode Island, have invented a new and useful Improvement in Snow-Excluding Arctics; and I hereby declare that the following is a full, clear, and exact description of the same, reference being had to the accompanying drawings, forming part of this specification.

Rubber overshoes extending above the instep having the quarters extending over the vamp and secured together by a suitable fastening device above the instep are known in the art as "arctic" overshoes. Some of these are provided with gussets, by which the spaces between the vamp and the quarters are closed, so as to prevent the entrance of snow. These are known in the art as "snow-excluders" and as "snow-excluding arctics." As heretofore constructed the vamp of these snow-excluding arctics was provided with laterally-extending flaps folded to form gussets. The outer edges of these flaps were secured by cementation to the forward ends of the quarters. There are several objections to this method of construction, one of which is that to secure a strong union between the extension-flaps of the vamp with the counters the cementation must be of considerable width and limits the extension of the opening through which the shoe-clad foot is inserted. Another objection is that the cemented joint is not as strong as is desirable, and a further objection is that the raw edges of the extended flap and the counters are exposed to wear and liable to fray and ravel out, whereby the appearance of the shoe is injured.

One object of the invention is to secure a wider opening for the insertion of the shoe-clad foot into the snow-excluding arctic.

Another object of the invention is to secure greater strength at the junction of the snow-excluding gussets with the quarters and expose no raw edges of the cloth.

The invention consists in the peculiar and novel construction by which the cloth of the counters is extended to form the gusset and connected with the vamp near the gutter or fold of the snow-excluding gusset, as will be more fully set forth hereinafter.

Figure 1 is a side view of a snow-excluding

arctic, the gusset formed by the extension of the counters being shown in broken lines. Fig. 2 is a front view of the same, showing the extensions of the counters joined to the vamp near the fold or gutter. Fig. 3 is a plan view of the counters, showing the gussets extending beyond the ends and made in one piece with the same.

In the drawings, *a* indicates the foxing of the lower part of the shoe. This part may be made in the usual manner, and its construction forms no part of my present invention.

b indicates the vamp of the snow-excluding arctic overshoe; *c*, the quarters; *c'*, the extensions of the quarters, which when secured to the vamp form the gussets; *c²*, the folded forward edges of the quarters, and *d d* the fastening devices by which the quarters are secured over the vamp above the instep.

In constructing the uppers of the snow-excluding arctic I cut the cloth forming the outer surface of the quarters with the extensions *c'* in one piece, preferably wide enough to allow the upper edge to be turned over and cemented to form the edge binding and prevent raveling of the cloth, as is indicated in broken lines in Fig. 3. The inner surface of the cloth is, as usual, faced with rubber. The usual strengthening-pieces—such as the pockets, the quarter-stays, and the buckle-stays—are secured to the quarters. The extensions *c' c'* are folded on the ends of the quarters, and the edges *c³ c³* are secured to corresponding edges on the vamp *b*, preferably on one side of the line *c⁴* of the gutter, in the usual manner by a joining-strip. As shown in the drawings, the vamp *b* is provided with the extensions *b' b'*, and these are united with the edges *c³ c³* of the quarters at a point beyond the fold or gutter *c⁴*; but these joints of the quarters to the vamp may be made at the line *c⁴* of the gutter or on either side thereof. By this construction the opening into the snow-excluding arctic overshoe for the admission of the shoe-clad foot is considerably larger than it was in the snow-excluding arctic of the same number or size in which the extensions *c' c'* of the gutters or folds were secured to the quarters by cementation, because the cementation of the gussets on the quarters requires a strip of cementation on the forward end of the quar-

ters, thereby placing the hinge-line about three-quarters of an inch back of the front edge of the two quarters and reducing the length of the upper edge of the material in-
5 closing the expanded opening by about three inches. In snow-excluding arctics this enlarged opening adds materially to the convenience in the use of the overshoes.

10 The folding over of the counter at its forward edge secures a slightly-cushioned rounded edge, and when the counters are secured over the instep and fastened firmer bearings of the counters on the vamp are secured along the edges c^2 c^2 than when these ends of the
15 counters are formed of separate pieces cemented together along the front edges of the counters for a distance of nearly an inch, permitting the entrance of fine snow between the folded gussets.

20 I am aware that arctic overshoes have been made in which the vamp and the quarters were formed in one piece. In this construction the quarters were jointed at the rear of the shoe, exposing the joint and making the
25 rear, which is exposed to the greatest strain in putting on or taking off the shoe, the weakest part. I do not claim this construction and have placed the joints in my improved
30 snow-excluding arctics near the gutter of the gussets, where they are concealed and exposed to the least strain and wear.

Having thus described my invention, I claim as new and desire to secure by Letters Patent—

1. In a snow-excluding arctic overshoe, the 35 combination with the vamp of the shoe and extensions on the vamp forming parts of the gussets, of quarters and extensions formed integral with the quarters forming the other parts of the gussets; whereby the extensions 40 of the vamp and quarters may be secured near the gutters of the gussets and a larger entrance for the shoe-clad foot secured, as described.

2. A snow-excluding arctic overshoe, hav- 45 ing the quarters and parts of the gussets connecting the quarters with the vamp formed in one piece without joint or seam, whereby the hinge-lines of the gussets are located on the extreme forward ends of the quarters and 50 the expansible opening is enlarged, as de- scribed.

3. A snow-excluding arctic overshoe in which the cloth forming the outer surface of the vamp extends in one piece over the vamp 55 and over parts of the gussets and the cloth forming the outer surface of the quarters extends in one piece over the quarters and the parts of the gussets connected with the quarters, as a new article of manufacture, where- 60 by the vamp and the quarters may be jointed at the gutters of the gussets, as described.

In witness whereof I have hereunto set my hand.

WILLIAM N. BUTTON.
